UNITED STATES PATENT OFFICE

ABRAHAM HALPIN, OF NEW YORK, N. Y.

DESIGN FOR A TENNIS RACKET PRESS OR SIMILAR ARTICLE

Application filed April 23, 1930. Serial No. 35,358. Term of patent 14 years.

To all whom it may concern:

Be it known that I, ABRAHAM HALPIN, a citizen of the United States, residing in New York city, (borough of Manhattan), in the county and State of New York, have invented a certain new, original, and ornamental Design for Tennis-Racket Presses or Similar Articles, of which the following is a specification, reference being had to the accompanying drawing, forming a part thereof, and of which Figure 1 is a plan view of a tennis-racket press with a tennis racket in dotted lines, and Fig. 2 is an edge view thereof, showing my new design.

I claim:

The ornamental design for a tennis racket press or similar article substantially as shown.

ABRAHAM HALPIN.
